UNITED STATES PATENT OFFICE.

JOSEPH H. WOOD, OF PITTSFIELD, MASSACHUSETTS, ASSIGNOR OF ONE-HALF TO ALBERT H. DAINTY, OF CHICAGO, ILLINOIS.

AUTOMATIC FIRE-ALARM.

SPECIFICATION forming part of Letters Patent No. 247,457, dated September 20, 1881.

Application filed September 4, 1880. (No model.)

To all whom it may concern:

Be it known that I, JOSEPH H. WOOD, a citizen of the United States, residing at Pittsfield, in the county of Berkshire and State of Massachusetts, have invented certain new and useful Improvements in Automatic Fire-Alarms, which are fully described in the following specification, reference being had to the accompanying drawings, in which—

10 Figure 1 represents a plan view of an alarm mechanism embodying my improvements; Fig. 2, a longitudinal section taken on the line xx , Fig. 1; Fig. 3, an elevation of the loose ratchet-wheel detached; and Fig. 4, a detailed elevation, showing the train of fan-gearing.

15 My invention relates to mechanism operating automatically when released to strike an alarm upon ordinary bells or gongs, being especially adapted for introduction in the bell-fries of churches and other buildings already provided with bells.

20 The invention consists in a series of hammers combined with operating devices, whereby successive and rapid strokes of the hammer 25 are produced successively upon the bell or gong.

25 The mechanism by means of which I carry out my invention will be hereinafter more specially described, and the improvements which 30 it is desired to secure by Letters Patent pointed out definitely in the claims.

35 In the drawings, A represents a suitable supporting-frame, which may be made of metal or other suitable material, and is locked and secured in position near the bell or gong B.

40 Arms C, in a series, are mounted loosely on the shaft D, at the end of the arm next to the bell. These frames project rearward, behind the shaft in nearly a horizontal direction, and 45 are turned up at their ends slightly to make a tappet, e, in which, preferably, an anti-friction roller, e', is mounted. Upon the shaft the arms are enlarged and provided with the circular slot c², concentric with the supporting-shaft.

45 The hammers E are mounted on the upper ends of arms e, the lower ends of which are loosely mounted on the shaft D, to permit the vibration of the hammers. One of these ham-

50 mers-arms is placed alongside each of the arms C, to which it is secured by means of the bolt e', passing through the circular slot c² to the corresponding hammer-arm, and secured by a nut, e², turned on one end, thereby clamping the hammer-arm to the arm C, and at the same 55 time permitting the adjustment of the hammer-arm with reference to the arm C to regulate the striking device.

50 Springs F are attached at their upper ends to a screw-bolt, f, fastened to the arms C, preferably by passing them through the circular slots in the latter. From this point of attachment the springs are carried forward and wound once or more around the boss or collar f', either made in one piece with or attached to the arm-piece C, and preferably on the side of the latter opposite to its corresponding hammer-arm. These collars are also loose on the shaft D. From them the springs extend downward to some suitable distance in the lower part of the 70 front end of the frame. In the drawings they are shown passed behind a shaft or rod, F', which is a cheap and efficient way of securing the springs.

75 The vibrating arms C, with their collars, are held in proper position on their supporting-shaft by means of adjustable collars d, set at any desired point on the shaft by means of fastening-screws d'.

80 The arms C, the hammers, and springs, are adjusted so that when at rest the springs will hold the hammers forward, so as to just touch, or nearly touch, the bell or gong. Obviously, whenever the rear ends of the arms C are depressed the hammers will be vibrated backward against the tension of the springs, which will then suddenly throw the hammers forward again as soon as the arms are released, and cause them to strike the bell. To produce this vibration of the operating-arms C, I attach a 85 series of cams, H, to a shaft, h, arranged in suitable bearings in the supporting-frame, just above the tappets e. These cams are shaped, as shown in Fig. 2 of the drawings, so that when brought in contact with their respective 90 tappets they will depress the rear ends of the arms C, and then will suddenly leave them, and the cams are arranged to come in working-

contact with the anti-friction rollers when the latter are used. The cams are also arranged on the shaft so as to operate successively or irregularly upon their respective arms, thereby 5 vibrating the hammers in regular succession to make strokes, one after the other. Obviously, therefore, a series of rapid strokes will be made upon the bell, their rapidity being governed by the number of hammers and the speed at 10 which the cam-shaft is revolved. To revolve this shaft a large gear-wheel, I, is attached to a shaft, i, mounted at the rear of the frame, on which a drum, J, is fixed. The wheel I engages with a pinion, K, loose on the cam-shaft, 15 but provided with a spring-pawl, k, which is arranged to engage with a ratchet, k', on the cam-shaft, these parts being constructed and arranged so that the pawl will engage with the ratchet and turn the shaft forward in the 20 proper direction to operate the hammers; but the pinion may be turned backward without rotating the shaft.

A weight, L, is fastened to a cord, l, which is wound on the drum J in a proper direction 25 to turn the shaft and gear-wheel I in the proper direction to rotate the cam-shaft by the pull on the cord. Obviously, when this mechanism is released, or left free to the influence of the weight, the cam-shaft will be rotated more or 30 less rapidly, thereby vibrating the hammers to produce a series of rapid strokes upon the bell to give an alarm; but, of course, as this mechanism is to be operated only when occasion requires, it is necessary to provide some stop device 35 to prevent its action under ordinary circumstances. This effect by means of a spring lever or pawl, M, one end of which is arranged to engage with a stop-cam, N, on a shaft, n, below the cam-shaft. This shaft is also provided 40 with a pinion, n', which engages with a gear-wheel, O, on a shaft, o, arranged between the shaft n and the cam-shaft, and also provided with a pinion, o', which engages with a gear-wheel, P, on the end of the cam-shaft. 45 The spring-lever is caused to engage with the cam-stop by means of a spring, m, the tension of which operates to hold the inner end of the lever in contact with the cam, and, obviously, this will prevent the forward rotation of the 50 shaft on which the cam is fixed by the engagement of the lever with the stop, and, through this stopping of the shaft n, effectually stop the rotation of the main cam-shaft, which is connected by gearing therewith; but when the 55 stop-lever is released from engagement with the stop-cam the mechanism will instantly be set in operation by the effect of the weight.

To release the stop-lever, a cord, m', is fastened to the outer end of the lever, and extended 60 down from the belfry to any place in the building desired, where it may be kept under lock and key, so as to be accessible only to those persons entrusted with a key.

A fan, Q, is fixed on the shaft n, outside of 65 the supporting-frame, which serves to regulate or balance the operation of the machine.

In the drawings three hammers are shown

and three cams, which are set on thirds, so that at each revolution of the cam-shaft each hammer will make a single stroke, in all three 70 strokes for each revolution of the shaft. This arrangement is, however, merely illustrative, for the principle of strokes may be regulated at will, according to the number of hammers and cams. 75

The relative size of the driving-gear and pinion on the cam-shaft is intended to be such that alarms may be given a number of times before the weight has run down. When, however, the weight has reached its limit the cord 80 may be wound up by a crank applied to the drum-shaft, the loose pinion on the cam-shaft permitting this backward revolution of the main gear-wheel.

Obviously, a spring motor may be substituted 85 for the weight, and other changes may be made in the particular mechanism herein shown and described, without modifying the principle of my invention. The hammer-arms, for instance, may be fastened directly to the operating-arms, 90 instead of being attached to the shaft, and the retracting-springs may be arranged differently, and the stop mechanism differently constructed and arranged; so that I do not limit myself to the precise construction and arrangement of 95 the special devices as described above.

This alarm mechanism is intended for application where bells are usually rung by hand to give alarms of fire, &c., and it may be readily applied in belfries already constructed and 100 provided with bells; or, if desired, for any special purpose, a structure with suitable gong or bell may be erected at any point and my alarm mechanism put in. The alarm will, of course, be sounded as long as the attendant holds 105 away the stop-lever, and the cord from the stop-lever may be run through a watch-tower, engine-house, or any other convenient place.

By applying the mechanism to bells differently tuned in different parts of a town the 110 location of a fire may be indicated to some extent, though this apparatus is not designed in this respect to take the place of the electric fire alarm.

The force of the stroke of the hammers may 115 be regulated to a great degree of nicety by adjusting the hammers with reference to the bell so that the springs will cause them to just strike the bell, or to strike with full force.

Having thus described my invention, what I 120 claim as new, and desire to secure by Letters Patent, is—

1. In a fire-alarm, a series of vibrating bell-hammers, in combination with a series of independent vibrating arms, to which the hammer-arms are adjustably attached, a series of cams mounted on a rotary shaft and arranged to act upon the vibrating arms, and a series of springs connected to the vibrating arms and arranged to operate both to throw the 130 hammers forward against the bell and to retract them after the blow is struck, substantially as described.

2. In a fire-alarm, a series of vibrating bell-

hammers, in combination with a series of independent vibrating arms, to which the hammer-arms are adjustably attached, a series of cams mounted on a rotary shaft and arranged to act upon the vibrating arms, a series of springs connected to the vibrating arms and arranged to operate both to throw the hammers forward against the bell and to retract them after the blow is struck, and a stop mechanism whereby the motor may be stopped and released at will, and a releasing-cord connected to the stop mechanism and extending outside the bell-tower, so that it may be reached from

below to throw the alarm into operation, substantially as described.

3. The vibrating arms C, provided with circular slots c', in combination with the hammer-arms, held to the former by means of bolt and clamping-nut, whereby the hammers may be adjusted with reference to the operating- arms, substantially as described.
